DOOR CLOSING DEVICE

Lawrence Richardson, Cambridge, Mass.

Application June 17, 1941, Serial No. 398,482

23 Claims. (Cl. 16—65)

This invention relates to door closers, and more particularly to a door closer employing unique spring means adapted to be energized during opening of the door and to be controlled so as to provide potential energy to effect closing of said door at different rates during different portions of its closing movement.

In the usual spring type of door closing devices or mechanisms the spring means has a closing force equal to the force applied to open the door, minus any friction losses that occur in the mechanism. The greatest force required to close the door must be present in the last few degrees of closure and, therefore, the greatest and equal effort must be exerted or applied at the beginning of the opening movement of the door. This opening force is often so great, especially with respect to the doors of sleeping cars, that it requires an unusual exertion on the part of the person attempting to open the door. The most common method so far devised of reducing the opening force is to construct the closing device so as to require little opening force and permit the door to close rapidly, utilizing the dynamic energy of the door to build up a high static force effective at the end of the closing movement of the door to latch the same. This effect is referred to as "slamming the door shut." Such devices, however, are dangerous and the fingers of many persons have been injured by being caught between the edge of the door and the jamb as the door "slammed" shut.

Outside of the relatively last few degrees of closing movement of the door, only a small force is usually needed to move the door toward closed position. Hence, the ideal door closing device is one which requires: a moderate opening force, a small closing force from its full open position to within a few degrees of closure, and a relatively large force from that point to closed position so that the latching of the door will be assured without any "slamming" effect. The present invention is so arranged and constructed that it fulfills all of the above requirements.

It is well known that one of the most positive means of storing energy is a spring. In the construction of the present door closer, a suitable main spring is wound during opening movement of the door to store potential energy therein to subsequently effect closing of the door. A relatively small auxiliary spring is arranged so that it is wound during a portion of the closing movement of the door, the energy for winding said auxiliary spring being "robbed" from the potential energy of the main spring, with the result

that the door is caused to close at a slowed-rate while the auxiliary spring is being wound. Thus, during the winding of the auxiliary spring, the net closing force is the difference between the energy of the main spring and that diverted to wind the auxiliary spring. The arrangement is also such that the energy stored in the auxiliary spring is released or discharged as the door nears its fully closed position so that this energy is made available to supplement that remaining in the main spring to increase the closing rate of the door and cause it to close with sufficient force to assure latching. In other words, the net closing force available at the moment of closing is the sum of the energy absorbed by the auxiliary spring plus the potential energy remaining in the main spring so that a relatively high closing force is made available to latch the door.

One of the principal objects of the invention is to provide a door closing mechanism which will enable a door to be opened with a minimum of effort but which will provide all of the force necessary at the end of the closing movement of the door to effect latching of the door in closed position.

Another object of the invention is to provide a door closer arranged so that it will cause a door to close at a slowed-rate until the door reaches its nearly fully closed position and will then effect an increase in the closing rate of the door sufficient to provide latching.

Another object of the invention is to provide a door closer arranged so that it will eliminate the danger of injuring the fingers of a person, should they be positioned between the door and jamb as the door closes.

A further object of the invention is to provide a spring type door closer having means for adjusting the tension of the spring means as required for a given installation.

Still another object of the invention is to provide a door closer adapted to receive one or more springs suitable for controlling the closing of doors of various size and weight, and whose initial tension may be varied as required.

A still further object of the invention is to provide a door closer which is relatively simple in construction and inexpensive to manufacture.

Other and further objects of the invention will be apparent from the following description taken in conjunction with the accompanying drawings, in which:

Fig. 1 is a fragmentary elevational view of a door closer mechanism embodying the principles of the present invention and showing one way of

operatively connecting the same with a door and door jamb;

Fig. 2 is a somewhat schematic plan view of the door closer shown in Fig. 1;

Fig. 3 is an enlarged plan view of the portion of the door closer which is preferably mounted upon the door;

Fig. 4 is a sectional view taken on the line 4—4 of Fig. 3;

Fig. 5 is a bottom plan view of the door closer;

Fig. 6 is a somewhat diagrammatic view showing the operative relation of the parts comprising the door closer when the door is in its nearly full-open position, the main spring at this time being already wound;

Fig. 7 is a similar view showing the relative position of the parts of the door closer when the door is about half-closed, that is, on an angle of about 45°, or at the time winding of the auxiliary spring commences;

Fig. 8 illustrates the parts of the door closer mechanism when the door is in about the 30° position of its closing movement or while the auxiliary spring is being wound; and

Fig. 9 shows the relationship of the parts and the door when the door is nearly fully-closed, that is, when it is within about 5° of its fully closed position and the auxiliary spring is unwinding.

Referring now to Figs. 1 and 2, the door closer is generally indicated by the letter D and comprises a casing 1 having laterally extending flanges 2 adapted to be secured to the upper end of a door 3 by any suitable fastening means such as screws 4. The door closer D includes a main shaft 5 to which is connected one end of an actuating lever 6, a pin 6^a securing the same in assembled relation with said shaft. The opposite end of the lever 6 is pivotally connected by a pin 7 to one end of a link 8, and the opposite end of said link is pivotally connected by a pin 9 to a bracket 10 suitably mounted upon the trim 11 surrounding the door 3. The door 3 in turn is pivotally mounted upon hinges 12, one of which is shown in Fig. 1, it being understood that a suitable number of additional hinges are provided to properly support the weight of the door.

Referring now to Fig. 4, the door closer casing 1 has a flange 13 at its upper end surrounding a plain circular opening 14 and a flange 15 at its lower end surrounding a threaded opening 16. A chamber 17 for a main spring 18 lies between the flanges 13 and 15, and a relatively small chamber 19 for an auxiliary spring 20 is arranged at one side of the chamber 17. A cover plate 21 forms a closure for the chambers 17 and 19 and is secured in place by machine screws 22 circumferentially spaced, as best shown in Fig. 3. The plate 21 is apertured at 23 for the reception of a reduced portion 24 formed at the upper end of the main shaft 5. The lower end of the shaft 5 extends through an aperture 25 formed in a circular plug 26 threadedly mounted in the opening 16. One end 27 of the main spring 18 extends through an opening 28 in the main shaft 5 and the opposite end 29 of said main spring extends through an opening 30 in the plug 26 as best shown in Fig. 4.

The plug 26 is provided with a central hexagonal boss 31 (Fig. 5) adapted to be engaged by a suitable wrench to effect adjustment of said plug in the threaded opening 16. A series of circumferentially spaced axially extending notches 32 is formed in the periphery of the plug 26. A locking screw 33 having a reduced plain end 34

of approximately the same circumferential width as the notches 32 is threadedly mounted in an opening 35 extending radially through the flange 15 so that the plug 26 may be rotated to place a desired initial tension in the main spring 18, and locked in the desired position of adjustment by rotating the lock screw 33 sufficiently to engage the reduced extension 34 with one of the notches 32.

The door closer D also includes an auxiliary shaft 37 (Fig. 4) having a reduced extension 38 at its upper end projecting through an aperture 39 in the cover plate 21. The lower end of the auxiliary shaft 37 projects through an opening 40 in a plug 41 threadedly mounted in an opening 42 in the casing 1. The upper end of the auxiliary spring 20 extends through a transverse opening 43 in the auxiliary shaft 37 and the lower end of said auxiliary spring extends through an opening 44 in the plug 41. The plug 41 includes a central hexagonal boss 46, and peripheral notches 47 similar to those provided in the plug 26, whereby the plug 41 can be turned to adjust the tension of the auxiliary spring 20. A locking screw 48 is threadedly mounted in an opening 49 in order to provide for locking of the plug 41 in adjusted position in the same manner described in connection with the tensioning of the main spring 18.

A cam-carrying plate 51 (Fig. 4) is non-rotatably mounted upon the reduced portion 24 of the main shaft 5 and is secured in position above the cover 21 by a pin 52 so that said cam plate and shaft rotate as a unit whenever the lever 6 is turned during the opening and closing movements of the door 3. For convenience in illustration and explanation, the parts in Figs. 1 and 3 have been shown in the position they assume when the door is in its fully closed position. On the other hand, Fig. 6 shows the door 3 in its nearly full-open position. It will be apparent from a comparison of these figures that during the opening movement of the door, the lever 6 is rotated in a counterclockwise direction relative to the casing 1, thereby effecting winding of the main spring 18 and the storing of potential energy in said spring to effect a return or closing of the door; the cam plate 51 being rotated through the same angle as the lever 6 because both are fixed to the main shaft 5. The return rotational movement of the cam plate 51 is utilized to effect winding of the auxiliary spring 20 through cam elements carried by said plate and generally indicated by 53 and 54, respectively (which will be described in detail later); it being understood that during the closing movement of the door 3 the main spring 18 tends to rotate the lever 6 and cam plate 51 in a clockwise direction. Hence, it will be apparent that any energy transmitted through the cam plate 51 to effect winding of the auxiliary spring 20 (as described hereinafter) will require the door 3 to close at a slowed-rate.

An arm 55 is secured by a pin 56 to the reduced portion 38 of the auxiliary shaft 37. The tendency of the auxiliary spring 20 is to rotate the arm 55 in a clockwise direction as viewed in Fig. 3 and a stop 57 is therefore mounted on the cover plate 21 to limit the angular movement of the arm 55 in said direction.

The arm 55 is generally triangular in shape, as best shown in Fig. 3, and the apex of said arm may be said to be fixedly secured to the auxiliary shaft 37 with the corner portions 58 and 59 of said arm disposed on opposite sides of the main

shaft 5. The portions 58 and 59 carry a roller 60 and 61, respectively, suitably mounted upon small conventional ball bearings (not shown) to reduce friction, said rollers being operatively mounted by the screws 62 and 63. The base of the triangular arm 55 is cut away as indicated at 64 to provide for limited angular movement of said arm with respect to the hub portion of the cam plate 51. In this connection it will be noted that the axis of the rollers 60 and 61, respectively, and the axis of the main shaft 5, all lie the same distance from the axis of the auxiliary shaft 37. This arrangement precludes binding of the rollers 60 and 61 and cam elements 53 and 54.

The cam elements 53 and 54, carried by the cam plate 51, are so shaped as to provide for complementary engagement with the rollers 60 and 61 carried by the arm 55, which serves to wind the auxiliary spring 20. The cam element 53 includes an inner concentric portion 65 and an outer concentric portion 66, both of which are cooperable with the roller 61. The portions 65 and 66 are connected by a cam surface 67 adapted to engage with the roller 61 to effect winding of the auxiliary spring during the closing movement of the door, as best illustrated in Fig. 8, and a cam surface 68 adapted to engage with said roller to control the unwinding of said auxiliary spring when the door 3 has reached its nearly-closed position, as best illustrated in Fig. 9. The outer concentric portion 66 provides a dwell between winding and release or unwinding of the auxiliary spring 20, so that the release can be designed to occur at any desired angle, say, 10° before the door 3 reaches its fully-closed position.

The cam element 54 is also provided with concentric surfaces 69 and 70 which are cooperable with the other roller 60. A cam surface 71 connects the concentric portions 69 and 70 and is adapted to engage the roller 60 during the winding movement of the arm 55, as best indicated in Fig. 8. As has been previously stated, the roller 61 at this time is engaged with the cam surface 67 and, therefore, the cam surfaces 71 and 67 mutually cooperate to effect winding of the auxiliary spring 20. The concentric portions 69 and 70 of the cam element 54 are also connected by a cam surface 72 cooperable with the roller 60 when the auxiliary spring 20 is unwinding and the door 3 is in its nearly fully-closed position, as illustrated in Fig. 9. The roller 61 is now engaged with the cam surface 68 and aids in rotating the cam plate 51 and lever 6 to increase the closing rate of the door to assure latching.

In order to permit movement of the cam element 54 past the roller 60 and in order to "pick up" the roller 60 to effect winding of the auxiliary spring 20, as when the cam plate 51 is moved from the position shown in Figs. 1 and 3 to that shown in Fig. 6, a latch 73 is pivotally mounted upon the cam element 54 at one end of the concentric surface 69 by a pin 74. The cam element 54 is cut away to provide a radial shoulder 75 and the latch 73 is provided with an end surface 76 adapted to engage said shoulder to prevent relative rotational movement of said latch in one direction relative to said cam element. The surface 76 is yieldably retained in engagement with the shoulder 75 by a spring strip 77 anchored at one end to the underside of the cam plate 51 by a rivet 78; the opposite end of said spring strip engaging a pin 79 carried

by said latch and extending through an arcuate slot 80 in said cam plate.

During the opening movement of the door 3, or in other words, during the movement of the door from the closed position shown in Figs. 1 and 3 to the nearly full-open position shown in Fig. 6, the lever 6 and its associated cam plate 51 are rotated through an angle such that the cam element 54 and the latch 73 are carried past the roller 60. The pivotal and yieldable mounting for the latch 73 just described permits said latch to move inwardly to the position shown in dot-and-dash lines in Fig. 6 wherefrom it will be apparent that the latch 73 can be pivoted inwardly about the pin 74 to clear the roller 60 without in any way interfering with the rotary movement of the cam plate 51. It will be noted from Fig. 6 that neither of the rollers 60 and 61 is engaged by the cam elements 53 and 54 when the door is nearly wide open. However, as the door 3 closes, and particularly when it reaches about the half-closed or 45° position shown in Fig. 7, the latch 73 will engage with the roller 60 and cause it to ride up onto the cam surface 71, as shown in Fig. 8. As soon as the roller 60 is engaged by the latch 73, the arm 55 is caused to rotate counterclockwise relative to the casing 1 and the winding of the auxiliary spring 20 commences. The energy for such winding is diverted from the main spring 18, which was previously wound during the opening movement of the door 3 to store energy therein for effecting closing of said door. Thus, part of the closing energy of the main spring 18 is transferred to the auxiliary spring 20 so that less energy is available to return or close the door during this particular part of its movement and, accordingly, the door moves toward closed position at a slowed rate. As the winding action of the auxiliary spring 20 continues, the roller 61 engages the cam surface 67 so that both cam elements 53 and 54 now cooperate to effect winding of the auxiliary spring. Winding continues until the roller 61 rides onto the concentric surface 66 whereupon no further winding of the auxiliary spring 20 occurs for about 10° of closing movement of the door, or until the roller 61 rides off the concentric surface 66 onto the cam surface 68. The auxiliary spring 20 is then free to unload or unwind and the released energy of said auxiliary spring is now made available to aid (the main spring 18) in returning the arm 55 in a clockwise direction, thereby causing the roller 61 to bear against the cam surface 68 and the roller 60 to bear against the cam surface 72 so as to exert a positive closing force through the lever 6 to effect sudden closing of the door 3 at the end of its closing movement. Thus, the remaining energy of the main spring 18 normally tending to effect closing of the door is suddenly supplemented by the potential energy of the auxiliary spring 20 so that the door closes at a more rapid rate at the end of its closing movement. This increased rate of closing movement is such that positive latching of the door 3 must take place.

If the door should be pushed open again before it has fully closed, no harm or injury can occur to the parts and particularly the cam and roller elements inasmuch as their arrangement permits the same to be backed up or reversed in their action by the opening force applied to the door which counteracts the closing force of the spring or springs.

It will be apparent that the principles of the

invention disclosed herein may be embodied in devices varying in construction from that disclosed in detail herein without departing from the spirit of the invention or the scope of the appended claims.

I claim:

1. A door closing device comprising: a casing adapted to be mounted upon a door; a windable main spring in said casing; adjustable means for winding said main spring to place a desired initial tension in the same; a windable auxiliary spring; adjustable means for winding said auxiliary spring to place a desired initial tension in the same; a main shaft connected with said main spring to effect further winding thereof and storage of closing energy therein during the opening movement of said door; an auxiliary shaft connected with said auxiliary spring to effect winding thereof during the closing movement of said door; a cam plate non-rotatably secured to said main shaft; a pair of cam elements carried by said cam plate, one of said cam elements including a spring-pressed latch; a winding arm non-rotably secured to said auxiliary shaft; a pair of rollers carried by said winding arm, one roller being adapted to be engaged by each of said cam elements; stop means for positioning said winding arm in a predetermined initial position such that said latch can engage one of said rollers to start further winding of said auxiliary spring and absorb a part of the closing energy of said main spring during a part of the closing movement of said door to thereby cause said door to move toward closed position at a slowed rate, each of said cam elements having a cam surface adapted to engage with one of said rollers to effect continued winding of said auxiliary spring while said door is closing and a cam surface to permit unwinding of said auxiliary spring or discharge of the energy absorbed by said auxiliary spring from said main spring as said door reaches its nearly fully closed position, whereby the energy absorbed from said main spring by said auxiliary spring to effect a slowed closing rate is made available to supplement the remaining energy of said main spring to increase the closing rate of said door just as it reaches the end of its closing movement.

2. A door closing device comprising: means arranged to store a part of the energy expended during the opening movement of a door for use in effecting closing of said door; and substantially friction free means for absorbing a portion of said closing energy so that said door moves toward closed position at a slowed closing rate and for discharging said absorbed energy just as said door is about to completely close, whereby to then increase the energy tending to close said door to assure latching.

3. A door closer comprising: a casing adapted to be mounted upon a door; a main spring in said casing; an auxiliary spring in said casing; means for winding said main spring during opening movement of said door; and means for utilizing the energy of said main spring to effect winding of said auxiliary spring during a part of the closing movement of said door, said last-mentioned means being arranged to permit unwinding of said auxiliary spring and the release of its energy as said door reaches its nearly fully closed position.

4. A door check comprising: a casing adapted to be mounted upon a door; a main spring in said casing; means for adjusting the initial tension of said main spring; an auxiliary spring in

said casing; means for adjusting the initial tension of said auxiliary spring; means for effecting winding and further tensioning of said main spring during opening movement of said door; and means for utilizing the energy of said main spring for effecting winding of said auxiliary spring during closing movement of said door, said last-mentioned means being arranged to release the energy of said auxiliary spring as said door nears the end of its closing movement.

5. A door closer adapted to be operatively associated with a door including: means arranged to have energy stored therein during the opening movement of said door to provide potential energy for effecting closing of said door; substantially friction free means for absorbing a portion of the closing energy of said first-mentioned means during a part of the closing movement of said door so that said door will close at a slowed rate; and means for effecting a release of said absorbed energy as said door reaches its nearly fully closed position, whereby to supplement the remaining potential energy of said first-mentioned means and assure latching of said door.

6. A door closer adapted to be operatively associated with a door comprising: means arranged to have energy stored therein during the opening movement of said door to provide potential energy for effecting closing of said door; and a substantially friction free mechanism including means for absorbing a portion of the closing energy of said first-mentioned means during a part of the closing movement of said door so that said door will close at a slowed rate, said mechanism being arranged to release said absorbed energy as said door reaches its nearly fully closed position, whereby to supplement the remaining potential energy of said first-mentioned means and assure latching of said door.

7. A door closer comprising: a casing adapted to be mounted upon a door; a main spring in said casing; an auxiliary spring in said casing; means for winding said main spring during the opening movement of said door; and means utilizing the energy of said main spring for effecting winding of said auxiliary spring during closing movement of said door, said last-mentioned means being arranged to permit unwinding of said auxiliary spring as said door reaches its nearly fully closed position.

8. A door closer adapted to be operatively associated with a door comprising: a windable spring arranged to be wound to store energy therein during the opening movement of said door to provide potential energy for effecting closing of said door; means for winding said spring during the opening movement of said door; and a mechanism including a windable auxiliary spring for absorbing a portion of the closing energy of said first-mentioned spring during a part of the closing movement of said door so that said door will close at a slowed rate, said mechanism being arranged to release the energy absorbed by said auxiliary spring as said door reaches its nearly fully closed position, whereby to supplement the remaining potential energy of said first-mentioned spring and increase the closing rate of said door.

9. A door closer comprising: a casing having a plurality of chambers; a main spring in one of said chambers; an auxiliary spring in another of said chambers; a main shaft arranged to effect winding of said main spring; an auxiliary shaft arranged to effect winding of said auxiliary

spring; a lever secured to said main shaft and arranged to rotate the same to effect winding of said main spring during opening movement of said door; and cam means interposed between said main shaft and auxiliary shaft arranged to effect winding and discharge of said auxiliary spring during the closing movement of said door.

10. A door closer comprising: a casing having a large chamber and a relatively small chamber; a main spring in said large chamber; an auxiliary spring in said relatively small chamber; a main shaft in said large chamber, one end of said main spring being connected with said main shaft and the opposite end of said main spring being connected with said casing; an auxiliary shaft in said small chamber, one end of said auxiliary spring being connected with said auxiliary shaft and the opposite end of said auxiliary spring being connected with said casing; a lever secured to said main shaft arranged to effect winding of said main spring during opening movement of said door; and means interposed between said main shaft and auxiliary shaft arranged to effect winding and release of said auxiliary spring during the closing movement of said door.

11. A door closer comprising: a casing having a large chamber and a relatively small chamber; a main spring in said large chamber; means for adjusting the initial tension of said main spring; an auxiliary spring in said relatively small chamber; means for adjusting the initial tension of said auxiliary spring; a main shaft in said large chamber, one end of said main spring being connected with said main shaft and the opposite end of said main spring being connected with the adjusting means for said main spring; an auxiliary shaft in said small chamber, one end of said auxiliary spring being connected with said auxiliary shaft and the opposite end of said auxiliary spring being connected with the adjusting means for said auxiliary spring; a lever secured to said main shaft arranged to effect winding of said main spring during opening movement of said door; and means interposed between said main shaft and auxiliary shaft arranged to effect winding and release of said auxiliary spring during the closing movement of said door.

12. A door closer comprising: a generally cylindrical casing adapted to be mounted upon a door, said casing having an open ended chamber formed therein; a threaded plug closing one end of said chamber; a closure plate closing the opposite end of said chamber; a shaft extending axially across said chamber having portions rotatably mounted in said plug and cover plate, respectively; a windable spring in said chamber, one end of said spring being connected to said shaft and the opposite end of said spring being connected to said plug, the peripheral edge of said plug being provided with a series of circumferentially spaced notches; a locking screw carried by said casing and having an end portion adapted to extend into one of said notches to lock said plug in adjusted position; and a lever connected to said shaft to effect rotation of said shaft and winding of said spring during opening movement of said door.

13. A door closer comprising: a casing adapted to be mounted upon a door; a main spring in said casing; an auxiliary spring in said casing; means including a main shaft for effecting winding of said main spring during opening movement of said door; a cam plate non-rotatably

secured to said main shaft, a cam element mounted upon said cam plate; and means for effecting winding of said auxiliary spring including an auxiliary shaft, an arm non-rotatably secured to said auxiliary shaft and a roller carried by said arm cooperable with said cam element.

14. A door closer adapted to be mounted upon a door comprising: a main spring; a rotatable main shaft arranged to effect winding of said main spring during opening movement of said door; an auxiliary spring; a rotatable auxiliary shaft adapted to effect winding of said auxiliary spring; a cam element rotatable with said main shaft; a winding arm non-rotatably secured to said auxiliary shaft; and a roller carried by said winding arm cooperable with said cam element, said cam element including a cam surface adapted to engage said roller to effect winding of said auxiliary spring and a second cam surface adapted to permit unwinding of said auxiliary spring.

15. A door closer adapted to be mounted upon a door comprising: a windable main spring; a rotatable main shaft arranged to effect winding of said main spring during opening movement of said door; a windable auxiliary spring; a rotatable auxiliary shaft adapted to effect winding of said auxiliary spring; a cam element rotatable with said main shaft; a winding arm non-rotatably secured to said auxiliary shaft; and a roller carried by said winding arm cooperable with said cam element, said cam element comprising a concentric portion, a cam surface adapted to engage said roller to effect winding of said auxiliary spring, a second cam surface adapted to permit unwinding of said auxiliary spring, and a latch pivotally mounted at one end of said concentric portion and arranged to engage said roller during rotation of said main shaft in one direction to cause said roller to ride up onto said first-mentioned cam surface to effect winding of said auxiliary spring during unwinding of said main spring.

16. A door closer comprising: a casing adapted to be mounted upon a door; a main spring in said casing; an auxiliary spring in said casing; means including a main shaft for effecting winding of said main spring during opening movement of said door; a cam plate non-rotatably secured to said main shaft; a plurality of cam elements mounted upon said cam plate; and means for effecting winding of said auxiliary spring including an auxiliary shaft, an arm non-rotatably secured to said auxiliary shaft, and rollers carried by said arm, one roller being cooperable with each of said cam elements.

17. A door closer comprising: a casing adapted to be mounted upon a door; a windable main spring in said casing; a windable auxiliary spring in said casing; a main shaft connected with said main spring to effect winding thereof during opening movement of said door; an auxiliary shaft connected with said auxiliary spring; a cam plate non-rotatably secured to said main shaft; a pair of cam elements carried by said cam plate; a winding arm non-rotatably secured to said auxiliary shaft; a pair of rollers carried by said winding arm, one roller being adapted to be engaged by each of said cam elements; means for positioning said winding arm in a predetermined initial position such that said cam elements can engage said rollers, each of said cam elements having a cam surface adapted to engage with a roller to effect winding and to permit release of

70
75

said auxiliary spring during the closing movement of said door.

18. A door closer comprising: a casing adapted to be mounted upon a door; a windable main spring in said casing; adjustable means for winding said main spring to initially tension the same; a windable auxiliary spring in said casing; adjustable means for winding said auxiliary spring to initially tension the same; a main shaft connected with said main spring to effect further winding thereof during opening movement of said door; an auxiliary shaft connected with said auxiliary spring; a cam plate non-rotatably secured to said main shaft; a pair of cam elements carried by said cam plate; a winding arm non-rotatably secured to said auxiliary shaft; a pair of rollers carried by said winding arm, one roller being adapted to be engaged by each of said cam elements; stop means for positioning said winding arm in a predetermined initial position such that said cam elements can engage said rollers, each of said cam elements having a cam surface adapted to engage with a roller to effect winding and to permit release of said auxiliary spring during the closing movement of said door.

19. A door closer comprising: means arranged to have energy stored therein during the opening movement of a door; and means for absorbing a portion of the energy stored in said first-mentioned means and then releasing the absorbed energy derived from said first-mentioned means during the closing movement of said door.

20. A door closer comprising: a casing adapted to be mounted upon a door; a windable coil spring in said casing; means for winding said coil spring during the opening movement of said door to

store closing energy therein; and means for absorbing a portion of the energy stored in said coil spring and then releasing the absorbed energy derived from said coil spring during the closing movement of said door.

21. A door closer comprising: means arranged to have energy stored therein during the opening movement of a door; and means for absorbing a portion of said energy and then releasing the absorbed energy derived from said first-mentioned means during the closing movement of said door, said energy absorbing occurring only during a portion of said closing movement of said door.

22. A door closer comprising: a casing adapted to be mounted upon a door; a windable coil spring in said casing; means for winding said coil spring during the opening movement of said door to store closing energy therein; and means for absorbing a portion of said energy and then releasing the absorbed energy derived from said coil spring during the closing movement of said door, said energy absorbing occurring during only a portion of said closing movement of said door.

23. A door closer comprising: means arranged to have energy stored during the opening movement of a door; and means for absorbing a portion of said energy and then releasing the absorbed energy derived from said first-mentioned means during the closing movement of said door, said absorbing and releasing means including means arranged and constructed so that the absorption of energy commences when said door is about 45° from closed position and the release of the absorbed energy occurs when the door is about 10° from closed position.
